UNITED STATES PATENT OFFICE.

CHARLES L. GLAFCKE, OF MICHIGAN CITY, INDIANA.

COBBLING OUTFIT.

1,426,289.

Specification of Letters Patent. Patented Aug. 15, 1922.

Application filed April 18, 1919. Serial No. 290,934.

To all whom it may concern:

Be it known that I, CHARLES L. GLAFCKE, a citizen of the United States, and a resident of the city of Michigan City, county of 5 Laporte, and State of Indiana, have invented certain new and useful Improvements in Cobbling Outfits, of which the following is a specification.

My invention relates to improvements in 10 cobbling outfits, and has for its object the provision of an improved construction of this character especially adapted for mounting various types of cobbler's lasts and holding boots or shoes in operative relation 15 therewith.

Other objects will appear hereinafter.

The invention consists in the combinations and arrangements of parts hereinafter described and claimed.

20 The invention will be best understood by reference to the accompanying drawings forming a part of this specification, and in which,

Fig. 1, is a side view of an outfit embodying the invention, showing a shoe in section in position of use thereon,

Fig. 2, a vertical section taken at right angles to Fig. 1, and

Fig. 3, a detail view of a slightly modified form of construction, for securing the binding strap of the device in place.

The preferred form of construction, as illustrated in Figs. 1 and 2, comprises a pedestal in the form of a vertical pipe section 35 4, having a circular base 4' at its lower end adapted to be secured to a floor, or other suitable support, and at its upper end a tubular socket 5 threaded thereon. The socket 5 is adapted to receive the stem 6 of an ordinary boot or shoe last 7, a set of lasts being 40 each provided with one of the stems 6 so as to render them readily interchangeable on the pedestal 4. A binding head 8 is slidably mounted on pedestal 4 and carries laterally 45 extending perforated ears or lugs 9, to which are attached wire loops 10 adapted to engage snap hooks 11 at the lower ends of a looped strap 12 passing over the last 7 and adapted to hold a boot or shoe 13 in position 50 thereon, as shown. The head 8 is provided with laterally extending arms 14 to constitute foot rests or pedals, and an automatic locking lever 15 is hinged at 16 to the under side of one of the arms 14 and is provided 55 with a slightly oblong opening slidably engaging over pedestal 4, as indicated.

In use, the desired last is placed in position on top of the pedestal 4 and the boot or shoe fitted thereon in the usual manner, with the strap 12 passing around the instep portion thereof. Then downward pressure is applied by placing the foot upon one of the arms 14, which exerts binding tension on the strap 12 to hold the boot or shoe securely in place on the last. The leaf 15 will slide 65 freely on the pedestal 4 during downward movement of the head 8 in applying this binding tension, but automatically interlocks with said pedestal to prevent upward movements of the head 8 and consequent relief of the tension in strap 12. When it is desired to remove the boot or shoe, a slight upward pressure on the free end of the leaf 15 will release the tension in strap 12, whereupon the boot or shoe may be readily removed, and a new last and a new boot or shoe applied, as desired. The device is a simple 70 and effective one for the purpose and capable of economical manufacture.

In Fig. 3 I have illustrated a slightly different arrangement for securing the ends of the strap 12 to the head 8. In this arrangement the head is provided with pairs of adjacent perforated lugs 9' and a cross pin 10' adapted to engage the snap hook 11 on the 80 ends of strap 12. Otherwise the construction is identical with that already described, and the operation is the same. This arrangement furnishes a slightly better arrangement for securing the snap hooks 11 to 85 the binding head 8, in that it tends to keep the strap from falling off of the last or stand when the tension therein is relieved.

While I have illustrated and described the preferred form of construction for carrying 90 my invention into effect, this is capable of variation and modification without departing from the spirit of the invention. I, therefore, do not wish to be limited to the precise details of construction set forth, but 95 desire to avail myself of such variations and modifications as come within the scope of the appended claims.

Having described my invention, what I claim as new and desire to secure by Letters Patent is:—

1. A cobbling outfit comprising a support; a last on said support; a head freely slidable on said support; means for automatically securing said head in adjusted positions on said support; and a flexible binding loop secured to said head and passing 110

around said last, substantially as described.

2. A cobbling outfit comprising a pedestal; a last removably mounted on top of said pedestal; a head freely slideable on said pedestal; a laterally extending pressure-applying arm on said head; means for automatically securing said head in adjusted positions on said support; and a looped strap secured to said head and passing around

10 said last, substantially as described.

3. A cobbling outfit comprising a pedestal; a tubular socket at the upper end of said pedestal; a last provided with a stem removably fitting within said socket; a head freely 15 slideable vertically on said pedestal; laterally extending arms on said head; a leaf hinged at one end to the under side of one of said arms and having an oblong opening therein slidably engaging said pedestal; and a looped strap secured to said head and passing over said last, substantially as described.

4. A cobbling outfit comprising a pedestal; a last at the top of said pedestal; a head freely slideable on said pedestal; a laterally 20 extending pressure-applying arm on said

25

head; a leaf hinged at one end to the under side of said head and having an oblong opening therein slidably engaging said pedestal, the other end of said leaf being extended sufficiently to permit of the ready engagement thereof for releasing purposes; and a looped strap secured to said head and passing over said last, substantially as described.

5. A cobbling outfit comprising a smooth cylindrical pedestal; a last at the top of 30 said pedestal; a head loosely mounted on said pedestal and capable of free rotatable and slideable movement thereon; means for automatically securing said head in adjusted positions on said pedestal; and a flexible 35 binding loop secured to said head and passing around said last, substantially as described.

In testimony whereof I have signed my name to this specification in the presence of 40 two subscribing witnesses.

CHARLES L. GLAFCKE.
